UNITED STATES PATENT OFFICE.

DAVID KNOX, OF LYNN, MASSACHUSETTS.

LEATHER-ROLLING MACHINE.

SPECIFICATION forming part of Letters Patent No. 311,498, dated February 3, 1885.

Application filed November 3, 1884. (No model.)

To all whom it may concern:

Be it known that I, DAVID KNOX, of Lynn, in the county of Essex and State of Massachusetts, have invented certain Improvements in 5 Leather-Rolling Machines, of which the following is a specification.

This invention relates to machines for rolling or otherwise acting on leather or other material, having two rolls or rotating bodies, 10 one mounted in fixed bearings which are movable toward and from said fixed bearings to vary the pressure exerted on the rolls by the article passed between them, the invention being mainly intended for rolling leather.

15 The object of the invention is to provide improved means for moving or adjusting the movable roll with relation to its companion roll; and to this end it consists in the improvements which I will now proceed to describe and claim.

20 Of the accompanying drawings, forming a part of this specification, Figure 1 represents a perspective view of a leather-rolling machine provided with my improvements. Fig. 2 represents a side elevation of the adjustable lower roll and its supporting and adjusting mechanism. Fig. 3 is a side view of the treadle and its connecting-link. Fig. 4 represents a perspective view of the wedges whereby the lower roll is adjusted.

25 The same letters of reference indicate the same parts in all the figures.

In the drawings, *a* represents standards, which, with the connecting-bars *b b*, constitute 30 the frame of the machine.

35 *c* and *d* represent the rolls which act on the leather or other material to be rolled. The upper roll, *c*, is journaled in fixed bearings in the standards *a a*, while the lower roll is journaled in boxes *e e*, which are vertically movable in slots in said standards. The boxes *e* are supported by the shorter arms of the two bell-crank levers *f f*, which are pivoted at *g g* to ears on the standards *a a*. The longer arms 40 of the levers *f f* project downwardly, and are connected by links *h h* to a transverse bar, *i*, passing through a slot in a yoke or holder, *j*, which is pivoted to a treadle, *k*, the latter being pivoted at its rear end to one of the connecting-bars *b*. A spring, *l*, secured at one 45 end to the treadle *k* and at its other end to another connecting-bar *b*, normally raises the

free end of said treadle, and draws the longer arms of the levers *f f* inwardly by means of the links *h h*, thus depressing the shorter arms of 55 said levers and allowing the boxes *e e* to drop and lower the roll *d*, which is thus separated from the upper roll. When the treadle is thus raised by the spring, the links *h h* are inclined downwardly from the bar *i* on the 60 treadle to the ends of the longer arms of the levers *f f*, as shown in Fig. 2; the links being thus held in position to act as members of a toggle-joint when they are moved into line, or approximately into line, with each other by 65 the depression of the treadle.

It will be seen that when the operator depresses the treadle he exerts a powerful outward pressure on the longer arms of the lever *f f* by means of the toggle-links, thus raising 70 the shorter arms of said levers and pressing the boxes *e e* and the roll *d* upwardly, the power applied to the treadle being multiplied by the described arrangement of the toggle-links and levers, so that a powerful up- 75 ward pressure may be exerted on the lower roll, which may be thus caused to exert any desired degree of pressure on the leather or other material being rolled. The slot *j'* in the yoke *j*, through which the bar *i* passes, is 80 wider than the thickness of said bar, so that as the treadle rises and falls the necessary variations of position which the yoke *j* experiences will not cause it to bind upon the bar, which is not movable laterally. The width of 85 the slot *j'*, together with the pivotal connection of the yoke *j* to the treadle, compensate for all the relative changes in the positions of the treadle and bar, caused by the swinging movements of the treadle, and make said move- 90 ments easy.

95 *m m* represent wedges upon which the boxes *e e* of the lower roll bear directly, said wedges being supported by blocks *n n*, interposed between their under sides and the shorter arms of the levers *f*, the boxes *e* having no positive connection with the blocks *n*, so that they can be raised and lowered independently of said blocks by moving the wedges *m m*, thus enabling the roll *b* to be adjusted as to its distance from the upper roll when it is not pressed against the upper roll by the mechanism above described. The wedges *m m* are moved in and out simultaneously by a connecting-bar, *s*, hav-

ing right-hand screw-threads at one end engaging the one wedge, and left-hand threads at the other end engaging the other wedge. The bar *s* is made in two sections, 2 and 3, 5 which are inserted in sockets in a coupling, 4, constituting the hub of a band-wheel, 5, and are adjustable lengthwise in said sockets, set-screws 6 holding the sections wherever they may be adjusted. By thus connecting the rod 10 *s*, I am enabled to adjust the length so that it may hold the wedges at any desired distance apart.

It will be seen that the force which the operator exerts on the roll *d* increases as the 15 links *h h* are being brought into line with each other until they are absolutely in alignment; hence the force becomes greater as the roll *d* rises, the operator being enabled to exert the greatest pressure when the roll *d* is already 20 pressing the leather against the upper roll, care being taken to adjust the wedges *m m* so that when the roll *d* is pressed upwardly to the farthest extent the links *h h* will not be brought quite into alignment.

25 I do not limit myself to the employment of the described mechanism to machines for rolling leather. The toggle-joint and levers may be used for imparting pressure to a roll or rotary body in other machines without departing from the spirit of my invention—for example, the machine for putting out and cleaning skins and leather, shown in the application of J. Hodskinson, Serial No. 147,135, filed herewith, the toggle-joint and levers being employed in said machine to press upwardly a cylinder on which a skin is supported while being operated on by spiral blades or flanges on a roll mounted in fixed bearings, the skin being pressed against said spiral blades by the 30 toggle-joint and levers, the spirally-flanged roll and the skin-supporting cylinder being equivalents of the rolls *c* and *d*, (shown in the present application,) so far as my improvements are concerned.

35 15 I claim—

1. As a means for imparting pressure to a movable roll or an equivalent pressure device,

two pivoted bell-crank levers having longer and shorter arms, and supporting the pressure device on their shorter arms, a treadle between the longer arms of said levers, and toggle-links connecting the treadle with the longer arms of the levers, said links being arranged to be brought into line, or approximately so, by the depression of the treadle, and thereby 55 act on the bell-crank levers, as set forth.

2. The combination of a roll or its specified equivalent journaled in fixed bearings, a co-operating roll or cylinder journaled in movable bearings, the two-armed pivoted levers supporting said movable bearings on their shorter arms, the toggle-links connected to the longer arms of said levers, and the treadle supporting said links, as set forth.

3. The combination of the supporting-frame, 65 the roll *c*, journaled in fixed bearings therein, the roll *d*, journaled in movable bearings, the pivoted two-armed levers *f f*, supporting said movable bearings on their shorter arms, the treadle located between the longer arms of the 70 levers, a spring whereby said treadle is normally raised, and the toggle-links connecting the treadle and the longer arms of the levers, as set forth.

4. The combination, with the movable bearings or boxes, of the wedges *m m*, supporting the boxes, and the connecting device composed of two sections, 2 3, and the socketed hub or coupling 4, in which said sections are adjustable, as set forth.

5. The combination of the levers *f f*, the links *h h*, the connecting-bar *i*, the treadle *k*, and the yoke *j*, pivoted to the treadle, and having a slot, *j'*, wider than the bar *i*, through which slot said bar passes, as set forth.

In testimony whereof I have signed my name to this specification, in the presence of two subscribing witnesses, this 23d day of October, 1884.

DAVID KNOX.
